UNITED STATES PATENT OFFICE.

GOTTHILF ANSGARIUS BETULANDER, OF SALTSJÖ-NACKA, SWEDEN.

TELEPHONE SYSTEM.

1,070,104.

Specification of Letters Patent.

Patented Aug. 12, 1913.

Application filed November 22, 1910. Serial No. 593,668.

To all whom it may concern:

Be it known that I, GOTTHILF ANSGARIUS BETULANDER, a subject of the Kingdom of Sweden, and resident of Saltsjö-Nacka, in 5 the Kingdom of Sweden, have invented certain new and useful Improvements in Telephone Systems, of which the following is a specification, reference being had therein to the accompanying drawing.

10 The present invention has for its object to prevent loss of current caused by leakage especially in sources of galvanic current, which deliver current periodically only to lines in which leakage may occur. Such 15 loss of current may occur for instance, by earth leakage in lines carried in the open air, in automatic telephone systems, the currents necessary for the automatic connection being sent out from an earthed battery through the 20 said lines, periodically and during short periods only. The battery being generally connected constantly to the line at the central-station it will send out a useless current, if leakage should occur on the line, which 25 current may damage the battery and disturb the connecting operation. According to this invention, the said disadvantage is overcome by the battery being normally separated from the line and, as occasion requires, connected to the same through a relay which 30 cuts in simultaneously a time switch adapted to disconnect the battery from the line after a certain period. The said relay, when being traversed by a current suitably puts 35 itself into a holding circuit containing the said time switch. Thus, the battery remains connected to the line as long as the holding circuit is closed, *i. e.* during that period at most in which the time switch is adjusted to 40 operate. If a longer impulse of current is to be sent through the line, the holding circuit may be led through the said line, the holding current forming the said impulse of current. For producing an impulse of 45 current through the relay cutting in the battery an auxiliary relay may suitably be used which is actuated by means of an alternating current and closes a circuit for a moment through the relay first mentioned, whereby 50 the same connects the battery with the line and puts itself into the holding circuit containing the time switch.

The annexed drawing shows the said invention as applied to an automatic telephone

system in which the automatic connection is 55 produced by means of impulses of current passing through the line branches and earth.

The diagram comprises two telephone apparatus I, II, each connected with automatic connecting apparatus A, B, respectively at 60 the telephone-exchange. The magneto-generator of the telephone apparatus is shown at 7. The arrangement is such that at every sub-station each line branch, 1 and 2, includes a switch 3, 4, contacts 5, 6, being provided for connecting the said switches with earth. One switch, 3, is used for establishing the desired connections and the other switch, 4, for disconnection.

The connecting apparatus connected with 70 the subscriber's telephone apparatus comprises a connecting electro-magnet, 9, a disconnecting electro-magnet, 10, a locking electro-magnet 11, whose armature 33, normally prevents the armature 22 of the connecting 75 electro-magnet from being attracted by the latter, and a cut-out electro-magnet 12, which by attracting the armature 37, carrying the two movable line contacts or springs 15, 16, during the connecting operation, prevents the said line-contacts from making contact with connecting wires leading to the connecting apparatus of subscribers with which no connection is desired. Of the two line branches 1, 2, 1 is connected with a relay 85 71, as also through a wire 13, with one of the connecting springs 15, and the other line branch 2 is connected with another relay 72, as also through a wire 14, with the other connecting spring 16. The windings of the relays are connected together, and further, each of the said windings is connected by wires 89, 83, with the armatures 79, 80, of the relays, 71 and 72 respectively, the stationary contacts 75, 76, of which are connected together by a wire 78, connected with the magnet 11, by a wire 90. The said relays 71, 72, have two additional contacts 73, 74, co-operating with two armatures 81 and 82, respectively connected to earth. The 90 windings of the connecting electro-magnet 9, and disconnecting electro-magnet 10 are connected together by a wire 17, and with the contacts 73, 74 respectively. The wire 17 is connected by a wire 24, including a 95 time-lag contact or time switch 77, with the wire 26, leading from the connecting battery 27. Further, a relay 84 is provided between 100 105

the line branches 1, 2, a condenser 85 being connected in series with the said relay. The stationary contact 86 of the relay 84 is connected with the wire 78 at the contact 76. The armature 87 of the said relay is connected with the wire 83. The relay last mentioned, the object of which is to cause the magnetizing of the relays 71, 72, when calling by means of induced current, may be dispensed with, if the armatures of the relays 71, 72, are made sufficiently sensitive.

The armature 22 of the connecting electro-magnet 9 is provided with a feeding arm 28, which by means of a tooth or the like engages the teeth of a connecting bar 29 or any other movable part, carrying the connecting springs 15, 16, connected with the line branches respectively, while the armature 23 of the disconnecting electro-magnet 10 is provided with a locking pawl 30, which, as the disconnecting electro-magnet is energized and its armature 23 is attracted, engages the teeth of the movable part 29 and prevents the said part falling. When the electro-magnets 9, 10, become deenergized, their armatures 22, 23, are moved to their normal positions shown in the drawing.

In order to prevent too great a load on the connecting battery 27 and exhausting it by leakage on the line or for any other reason, the time lag contact 77 is provided in the wire 26 between the battery 27 and the magnets 12, 11 and 9, 10 respectively, which, for instance, is controlled by a clockwork, disengaged by an electromagnet 88, the mechanism being so adapted that the contact 77 will be broken, only if a current passes through the wire 26 during a period which is somewhat longer than that required for the connecting operation, the contact being then immediately again closed.

Suppose the subscriber at substation I wishes to put himself in communication with substation II. He then closes the earth contact 5 for instance at his telephone apparatus I and rotates the armature of the magneto-generator 7 of said apparatus, whereby an alternating current passes through the relay 84, which attracts its armature 87, the following circuit being thereby established; earth, battery 27, wire 26, time-lag contact 77, electromagnets 12 and 11, wire 90, wire 78, contact 86, armature 87 and then partly through relay 71 partly through relay 72, line branches 1, 2, contacts 3, 4, contact 5 and earth. Owing to the said circuit the contacts 73, 75, 76, 74 are closed and are held in their closed positions, as the current now passes through the wire 83, to the relays 71, 72. At the same time the current from the wire 26 through the wires 24, 17, is divided into two parallel branches, comprising the connecting and disconnecting electro-magnets 9 and 10 respectively, contacts 73, 74 respectively and earth. As the electro-

magnet 11 now attracts its armature 33, the armature 22 of the connecting electro-magnet 9 is freed and is attracted by the said magnet 9. On account of the electromagnets 9, 10, having attracted their armatures, the tooth of the feeding arm 28 has passed the uppermost tooth of the bar 29 and entered into the notch beneath the said tooth, while the pawl 30 engages and holds the bar. The lower end of the feeding arm 28 has now passed the top end of the armature 23, the top end of which, consequently, enters the space between the bar 29 and the feeding arm. If now the connecting switch 3 of the substation I is forced downward, the current from the battery 27 ceases to flow through the relay 71, the armatures 79 and 81 are released and the current through the connecting electro-magnet 9 is broken at 73, so that the armature 22 and the feeding arm 28, acted upon by the spring 31, raises the bar 29 a distance corresponding to the length of a tooth, which is equal to the distance between the connecting wires. As the bar 29 is raised the end of the pawl 30 slips over a tooth of the bar and enters the notch nearest below that tooth, thus holding the bar in its raised position, in case the connecting switch 3 should again close the circuit through the electro-magnet 9.

In order that the calling subscriber may be able to bring the contact springs 15, 16, of his connecting apparatus A into contact with the contact wires 104, 114, of the apparatus of the subscriber, with which connection is desired, the bar 29 must be moved four steps according to the drawing. It follows from the preceding that, for this purpose, four interruptions must be made by means of the switch 3. The earth contacts 5, 6, are then broken before the switch 3 is allowed to return after the fourth interruption. On account of the break at the earth contacts 5, 6, the battery 27 ceases to supply current and the armature 23 with its pawl 30 is retracted by the spring 32, so that the pawl 30 is brought out of engagement with the bar 29 which is now kept in its raised position only by the feeding arm 28.

When it is desired, after conversation has been finished, to restore the connecting apparatus to its normal or resting position, the same operations are made as in establishing the desired connection, only with the difference that, instead of breaking the switch 3, the disconnecting switch 4 is now forced downward. By closing the earth contact 5 and rotating the magneto-generator 7 of the telephone apparatus, the electro-magnets 9 and 10 are caused, as before described, by the action of the relays 84, 71, 72, to attract their armatures 22, 23, respectively, and the lower end of the arm 28 then, as before, passes the top end of the armature 23. By forcing the disconnecting switch 4 down-

ward, an interruption by the action of the electro-magnet 72 is made in that branch of the circuit of battery 27 comprising the disconnecting electro-magnet 10, and the armature 23 is thus retracted by its spring 32, but as the top end of the armature 23 projects between the bar 29 and the arm 28 the latter is caused to follow, so that the tooth of the said arm is brought out of engagement with the bar, which is brought back by its own weight or by any other force into its normal position. Before the disconnecting switch 4 is allowed to return upward, the earth contacts 5, 6 are broken, whereby the branch of the circuit of battery 27 comprising the electro-magnet 9 is also broken. The armature 22 is then retracted by its spring 31 and pulls the arm 28 upward, and when the top end of the armature 23 releases the end of the arm 28, the latter enters into and engages the uppermost notch of the bar 29. If now, for instance, an earth leakage should occur in the line branch 1, the relay 71 will be traversed by a current even after the connecting period has finished, and then the contact 77 is broken after a certain period. Thereby the relay 71 becomes currentless and releases its armature, so that the battery, notwithstanding the following closing 30 of contact 77, cannot again be connected to the line before the next connecting operation. In case of earth leakage in the line branch 2 the relay 72 also remains current-carrying through the armature 80 until the 35 current is broken at the contact 77. In the indicated example of connection a greater leakage in the branch 2 would also render the connection quite impossible. In the drawing each connecting apparatus is provided with a time switch 77, but, of course,

a single switch may be used for sets of connecting apparatus or for the whole exchange.

What I claim is:

1. In safety devices for preventing loss of current by leakage the combination with a source of current and a line normally separated from the said source of current, of a relay, adapted to effect the connection of the said line with the source of current and a time switch adapted to disconnect the source of current from the line after a certain period. 45

2. In safety devices for preventing loss of current by leakage the combination with a source of current and a line normally separated from the said source of current, of a relay adapted to effect the connection of the said line with the source of current and a holding circuit for the said relay including a time switch. 55

3. In safety devices for preventing loss of current by leakage the combination with a source of current and a line normally separated from the said source of current, of a relay adapted to effect the connection of the said line with the source of current, and a time switch adapted to disconnect the source of current from the line after a certain period, an auxiliary relay and an auxiliary circuit including the relay first mentioned and a contact device operated by the auxiliary relay to close the auxiliary circuit. 65

In witness whereof, I have hereunto signed my name in the presence of two subscribing witnesses.

GOTTHILF ANSGARIUS BETULANDER.
